Inventor

United States Patent Office.

F. W. BROCKSIEPER, OF NEW HAVEN, CONNECTICUT, ASSIGNOR TO SARGENT AND COMPANY, OF SAME PLACE.

Design No. 3,026, dated May 12, 1868.

DESIGN FOR A BRACKET.

The Schedule referred to in these Letters Patent and making part of the same.

TO ALL WHOM IT MAY CONCERN:

Be it known that I, F. W. BROCKSIEPER, of New Haven, in the county of New Haven, and State of Connecticut, have invented a new Design for a Bracket; and I do hereby declare the following, when taken in connection with the accompanying drawings, to be a full, clear, and exact description of the same, and which said drawings constitute part of this specification, and represent, in—

Figure 1, a perspective view of the bracket, and in

Figure 2 the shelf detached.

This invention relates to a design for a wall-bracket, formed from cast metal, in imitation of carved wood. The shelf is composed of a rustic frame, filled with a branch and a single leaf in each side of the centre, the base reposing on a branch turning to the right and left, the branch or vine continuing in appearance above the shelf, so as to form a means of support to the shelf, and the centre support of the shelf below corresponding to either half of the base below, as clearly seen in the accompanying illustrations.

Having described my invention, what I claim as new, and desire to secure by Letters Patent, is—

The design for a bracket as herein described and illustrated.

Witnesses:

J. H. SHUMWAY,
A. J. TIBBITS.
